UNITED STATES PATENT OFFICE.

ALFRED J. MERLE, OF ALAMEDA, CALIFORNIA.

MOLD.

1,399,977.

Specification of Letters Patent. Patented Dec. 13, 1921.

Application filed June 12, 1920. Serial No. 388,530.

To all whom it may concern:

Be it known that I, ALFRED J. MERLE, a citizen of the United States, and a resident of Alameda, county of Alameda, and State 5 of California, have invented a new and useful Mold, of which the following is a specification.

My invention relates to molds and especially to molds for liquid-borne materials 10 from which the fluid is separated to condense the material in the mold.

Objects of the invention include the provision of a mold embodying improved means for releasing it from the molded material. 15 and for permitting the draining away of the liquid.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing 25 made by the said drawings and description, as I may adopt variations of the preferred form within the scope of my invention as set forth in the claims.

Referring to the drawings: Figure 1 is 30 a perspective view of my mold, portions being broken away to disclose the structure. Fig. 2 is a vertical sectional view through one end of the mold, in the plane of the tie rods. Fig. 3 is a vertical sectional view 35 in a plane indicated by line 3-3' of Fig. 2.

The mold of my invention is used in the formation of blocks from a fluid mixture of solids in a liquid vehicle, such for example as a water-borne mixture of asbestos fiber 40 and magnesia. Provision is made for the liquid to drain away leaving the mold filled with the solids. Provision is also made for releasing the wet block of material from the mold.

45 In common practice a battery of molds open at opposite sides are placed together with apertured side plates between the molds. The fluid mixture is then pumped into the molds, the liquid draining away, 50 until the molds are packed. They are then separated and rapped to loosen the wet blocks so that the blocks may be freed from the mold. This method frequently results in breaking the block and is so destructive 55 of the edges that an excessive amount of the

block must be trimmed off to leave a whole rectangular block of the desired size. Furthermore such blocks are not homogeneous, being softer in the center, because of the defective drainage from that portion. With 60 my mold, the resultant block is more nearly homogeneous, because the liquid from the mixture is permitted to escape from all sides of the block and the block is removable from the mold with no danger of breakage or injury, so that in truing up the block only a small amount needs to be trimmed off.

My mold comprises bottom piece 2 and top piece 3 between which end pieces 4 are interposed. Two tie rods 6 spaced apart a 70 suitable distance pass through top, bottom and end piece at each end of the mold. Nuts 7 on the lower ends of the rod and nuts 8 near the top of the rods provide means for permanently clamping the end pieces of the 75 mold to the bottom piece. These nuts are countersunk flush with the lower face of the bottom piece and the upper end of the end pieces respectively. The upper portion of the rods forms a loose fit in the top mold 80 piece, and their ends, which extend a short distance beyond the upper face of the top piece are formed with edges 9 in which a roller 11 is eccentrically journaled by means of short studs 12. Fixed on each end of the 85 top piece 3 and pierced by the rods 6 is a plate 13 formed with slideways 14 inclosing the roller, and permitting it to move therein on the plate in a direction transverse to the axis of the roller, but without rising from 90 contact with the plate. A handle 16 for rotating the roller is fixed thereto, and normally contacts with the plate 13 on either side to fix the extremes of movement of the roller.

95 Thus, with rotation of the roller the slideways are moved longitudinally of the anchored tie rods, and the top piece 3 fixed to the slideways is correspondingly moved away from or toward the rest of the mold. The parts are so proportioned and adjusted 100 that when the handle at each end is in the position shown in Fig. 3, the eccentrically mounted roller is just past the dead center and clamps the top piece upon the ends. 105 When the handle is thrown over to the position indicated by the dotted lines, the roller is turned just past the dead center in the opposite direction, forcibly lifting the top piece free from the ends of the mold and 110

the block therein, and holding it in the raised position.

With the opening of the two-part mold as just described the inclosed block of material 5 is readily released without injury. After release of the block, return movement of the handles closes the mold and locks the parts together.

In order to provide for the rapid draining 10 away of the fluid, the inner or mold faces of the pieces 2, 3 and 4 are provided with grooves 17 extending from end to end of the pieces. These grooves in the case of the 15 top and bottom pieces open upon the ends of the mold and permit easy escape of the liquid. Furthermore a wire may readily be run through the grooves to free accumulations therein, without separating the various parts. As shown in Fig. 1, the grooves 20 in the end pieces are alined with those in the bottom and top pieces.

Overlying the grooves is a foraminated plate 18, and over the plate is a fabric covering 19. These may be held in place by 25 any suitable means such as by wedging the edges thereof in slots 21 adjacent the edges of the pieces. A smooth molding surface is thus presented, through which the liquid from the mixture readily passes into the 30 draining grooves.

I claim:

1. A mold comprising bottom and end pieces, a top piece on said end pieces, tie rods anchored in said bottom-and-end structure and passing through said top piece, and means interposed between the ends of said tie rods and said top piece for lifting the

top piece from and clamping it to the rest of the mold.

2. A mold comprising bottom and end 40 pieces, a top piece on said end pieces, tie rods anchored in said bottom-and-end structure and passing through said top piece, a roller eccentrically journaled in said tie rods, slideways on said top piece in which said 45 roller is confined, and means for turning said roller.

3. A mold comprising bottom and end pieces, a top piece on said end piece, tie rods passing through said bottom, end and top 50 pieces, means on said rod for clamping permanently together the bottom and end pieces, and means interposed between the ends of the tie rods and the top piece for lifting the top piece from and clamping it 55 to the end pieces.

4. A mold clamp, comprising rods anchorable in one portion of the mold, a roller eccentrically journaled on said tie rods, 60 slideways fixable on a second portion of the mold and in which said roller is confined, and a handle for turning said roller to move said slideways longitudinally of said rods.

5. A mold clamp comprising rods anchorable in one portion of the mold, a plate 65 pierced by said rods fixable to a second portion of said mold, and means interposed between said rods and said plate for causing relative movement therebetween longitudinally of the rods.

In testimony whereof, I have hereunto set 70 my hand.

ALFRED J. MERLE.
